UNITED STATES PATENT OFFICE.

WALTER F. KOKEN AND ANTON J. PICHL, OF ST. LOUIS, MISSOURI.

VALVE MECHANISM FOR INTERNAL-COMBUSTION ENGINES.

1,161,221.

Specification of Letters Patent.

Patented Nov. 23, 1915.

Application filed December 22, 1913. Serial No. 808,058.

To all whom it may concern:

Be it known that we, WALTER F. KOKEN and ANTON J. PICHL, citizens of the United States, residing at the city of St. Louis, 5 State of Missouri, have invented certain new and useful Improvements in Valve Mechanisms for Internal-Combustion Engines, of which the following is a specification.

This invention relates to internal combustion engines of the type in which oscillating valves are employed for controlling the admission and exhaust of the gases to and from the cylinders.

The main object of our present invention 15 is to provide a multi-cylinder, four-cycle internal combustion engine of the general type mentioned, in which the oscillating valves are of novel design and are arranged in groups, each of which comprises a plurality of positively-actuated valves that 20 cooperate with all of the cylinders of the engine, the valves of one group controlling the inlet ports of certain cylinders and the exhaust ports of the remaining cylinders, and 25 the valves of the other group controlling the ports that are not governed by the valves of the group first referred to.

Another object is to provide a multi-cylinder, four-cycle engine that is equipped 30 with oscillating valves which are so designed and arranged that the combustible gases never enter or pass through the spaces in the valves through which the burnt gases escape from the cylinders.

35 And still another object is to provide an engine of the construction above described, in which each of certain of the valves consists of a hollow cylindrical-shaped member provided with two separate and distinct 40 compartments or chambers that register alternately with the inlet port of one cylinder and the exhaust port of a different cylinder when the engine is in operation.

45 Other objects and desirable features of our invention will be hereinafter pointed out.

Figure 1 of the drawings is a top plan view of an internal combustion engine embodying the present invention; Fig. 2 is a side elevation of same partly in section; 50 Fig. 3 is a sectional view on line 3—3 Fig. 2; Fig. 4 is a sectional view on the line 4—4, Fig. 3; Fig. 5 is a sectional view on the line 5—5, Fig. 3; Fig. 6 is a sectional view, on an enlarged scale, on the line 6—6, Fig. 3; 55 Fig. 7 is a perspective view, on an enlarged scale, of one of the shoes; Fig. 8 is a sec-

tional view, on an enlarged scale, on the line 8—8, Fig. 2; Fig. 9 is a sectional view, on an enlarged scale, on the line 9—9, Fig. 2; and Fig. 10 is a sectional view, on an enlarged 60 scale, on the line 10—10, Fig. 2.

The cylinders 1, 2, 3, and 4 have the pistons 5 adapted to operate therein, which pistons are connected separately to the cranks (not shown) of the crank-shaft 6 by means 65 of the connecting-rods 7 in the usual manner, said crank-shaft being adapted to rotate in the crank-casing 8 and having the fly-wheel 9 rigidly mounted on one end thereof. Each of said cylinders has an inlet port 10 and an exhaust port 11 preferably located in its head, which ports open into separate valve-casings or bearings 12, which are preferably disposed transversely in the top of the cylinder casing, the ports 70 10 and 11 of the several cylinders, in the case of an engine having four cylinders as illustrated in the drawings, being arranged so that the exhaust port 11 of the cylinder 1 opens into the first valve-casing 12, i. e., the 75 valve-casing at the right end of the engine, Fig. 2, the inlet port 10 of the cylinder 1 and the exhaust port 11 of the cylinder 2 open into the second valve-casing 12, the inlet ports 10 of the cylinders 2 and 3 open 80 into the third or middle valve-casing 12, the exhaust port 11 of the cylinder 3 and the inlet port 10 of the cylinder 4 open into the fourth valve-casing 12, and the exhaust port 11 of the cylinder 4 opens into the fifth 85 valve-casing 12, i. e., the valve-casing at the left end of the engine. The ends of the valve-casings 12 are closed by plates 13, which are secured to the sides of the cylinder casing adjacent to the top of same by bolts 90 14 or other suitable means, the plate 13 on one side of the cylinder casing having openings 15, which communicate separately with the second, third, and fourth valve-casings 12 and receive the branch connections of the 95 manifold 16, which has the usual connection with the carburetor 17, and the plate 13 on the other side of the cylinder casing, also, having openings 15, which communicate with the first, second, fourth, and fifth valve- 100 casings 12 and receive the branch connections of the exhaust pipe 18. Passages 19 between the valve-casings 12 and above the heads of the cylinders communicate with the water-jacket 20, which surrounds the cylinders, to allow the water which enters the water-jacket through the inlet pipe 21 to 105 110

circulate through said passages before discharging through the outlet pipe 22. A spark-plug 23 and a priming-valve 24 are provided for each cylinder, the spark-plugs being preferably located on one side of the engine and the priming-valves being located on the opposite side.

Each valve-casing 12 is preferably of cylindrical form and has a hollow cylindrical valve 25 revolvably supported therein, said valve casing having a slot 26 to allow an arm 27 borne by or secured to said valve to extend therethrough. The valves are arranged in two groups, each of which comprises a plurality of valves that coöperate with all of the cylinders of the engine, the valves of one group controlling the inlet ports of certain cylinders and the exhaust ports of the remaining cylinders, and the valves of the second group controlling the ports in the cylinders that are not governed by the valves of the first group. In the engine herein shown the valves 25 in the first, third and fifth valve casings 12, counting from right to left in Fig. 2, constitute one group and those in the second and fourth valve casing constitute the second group. The valve casings that receive the first and fifth valves of the first group are closed at one end and their opposite ends communicate with branches of the exhaust pipe 18, the valve casings that receive the intermediate valve of this group, namely, the third valve of the engine, being closed at one end and having its opposite end communicating with a branch of the intake manifold 16. Each of the second and fourth valves of the engine which constitute the second group, is divided by a partition 28 into two non-communicating compartments 29 and 30, the compartment 29 communicating with a branch of the manifold 16 and the compartment 30 communicating with a branch of the exhaust pipe 18. Communication between the inlet ports 10 and the exhaust ports 11 of the cylinders and the interior of their respective controlling valves 25 is established in proper sequence through passages 31 in the walls of said valves, the first valve having only one passage 31 to establish communication between same and the exhaust port 11 of the cylinder 1, the second valve having two passages 31 to establish communication between its compartments 29 and 30 and the inlet port 10 of the cylinder 2, respectively, the third valve having two passages 31 to establish communication between same and the inlet ports 10 of the cylinders 2 and 3, respectively, the fourth valve having two passages 31 to establish communication between its compartments 29 and 30 and the inlet port 10 of the cylinder 4 and the exhaust port 11 of the cylinder 3, respectively, and the fifth valve having only one

passage 31 to establish communication between same and the exhaust port 11 of the cylinder 4, when the valves are rocked in their casings in the manner now to be described. It will thus be seen that the valves 70 of each group coöperate with all of the cylinders and that the valves of the first group control the exhaust ports of the two end cylinders and the inlet ports of the two intermediate cylinders, and that the valves of 75 the second group control the inlet ports of the two end cylinders and the exhaust ports of the two intermediate cylinders. It will also be noted that the combustible gases never enter or pass through the spaces in 80 the valves through which the burnt gases escape from the cylinders.

Each arm 27 is pivotally attached at 82 to a rod 33, there being, in the case of the engine illustrated in the drawings, two of 85 such rods employed, one rod being connected to the arms 27 of the first group of valves composed of the middle and the two end valves 25, and the other rod being connected to the arms 27 of the other two valves 25, 90 constituting the second group as depicted in Figs. 1 and 2. Each rod 33 extends beyond one end of the engine and has its outer end pivotally connected at 34 to one end of a pin or rod 35. The free end of said pin 95 or rod 35 is slidably fitted in a longitudinal bore 36 in the upper end of a lever 37, which latter is pivotally attached to and between the outwardly-projecting arms 38 of a bracket 39 by a pin 40 or the like, said 100 bracket having a pair of inwardly-projecting arms 41, which arms 41 straddle a lug 42 borne by the cylinder casing and have slots 43 to receive a bolt 44 or a plurality of such bolts, by means of which said bracket 105 is adjustably secured to said lug. The lower end of each lever 37 extends through a slot 45 in the top of a housing 46 borne by the crank-casing 8 and, also, contains a longitudinal bore 36, in which the upper end of a pin or rod 47 is slidably fitted. Each pin 110 or rod 47 is provided at its lower end with an eye 48 to receive the outer end of a pin 49, which pin 49 is rotatably supported in a block 50, which is slidably mounted upon 115 by a guide-rod 51 or a plurality of such guide-rods supported in the end wall of the crank-casing 8 and the end wall of the housing 46, a cotter-pin 52 or other suitable means being attached to the outer end of the pin 49, in order to retain the eye 48 of the pin 47 upon the latter. The blocks 50, of which there is a pair, are preferably arranged to reciprocate substantially parallel to the axis of rotation of the crank-shaft 6 120 on opposite sides of the latter and are provided with relatively deep longitudinal grooves 53 in their faces, which grooves register with each other to receive a cylindrical member 54 borne by the crank-shaft 6 125 130

within the housing 46. Each pin 49 is provided on its inner end with an arcuate shoe 55, which is adapted to ride in the cam groove 56 in the periphery of the cylindrical member 54, said cam groove consisting of a right-hand screw-thread groove and a left-hand screw-thread groove, which screw-thread grooves cross at their middle points and connect at their ends so as to make the cam groove continuous, and the shoes 55 being located substantially 180 degrees apart in said cam groove. By this arrangement, when the crank shaft 6 is rotated, the shoes 55 travel in the cam groove 56 in the member 54 and thereby reciprocate the blocks 50, whereby the latter rock the levers 37, which, in turn, cause the rods 33 to rock the valves 25, with the result of causing the passages 31 in the valves 25 to open and close the inlet ports 10 and the exhaust ports 11 of the cylinders in proper sequence.

It will be understood that two complete revolutions of the crank-shaft 6 are necessary to effect a complete rocking movement of each valve 25. These valves 25 are preferably so arranged and their movements so timed that the passages 31 in said valves will open and close the inlet ports 10 and exhaust ports 11 of the cylinders in such sequence that the power or firing strokes of the pistons 5 within the cylinders 1, 2, 3, and 4 will take place in the following order, viz., 1, 3, 4, and 2. Referring to Fig. 2, it will be seen that the valves 25 occupy such positions that the first valve 25 closes the exhaust port 11 of the cylinder 1, the second valve 25 establishes communication between its inlet compartment 29 and the inlet port 10 of the cylinder 1 and closes the exhaust port 11 of the cylinder 2, the third valve 25 closes the inlet ports 10 of the cylinders 2 and 3, the fourth valve 25 establishes communication between its exhaust compartment 30 and the exhaust port 11 of the cylinder 3 and closes the inlet port 10 of the cylinder 4, and the fifth valve 25 closes the exhaust port of the cylinder 4, these positions being occupied by the valves 25 at the same time the cranks of the crank-shaft 6 occupy substantially horizontal positions, with the piston 5 within the cylinder 1 at the middle of its charging or suction stroke, the piston 5 within the cylinder 2 at the middle of its compression stroke, the piston 5 within the cylinder 3 at the middle of its exhausting stroke, and the piston 5 within the cylinder 4 at the middle of its power or firing stroke. It will be observed that, when the valves 25 occupy the positions just described, the first, third, and fifth valves 25 stand midway between the limits of their rocking movement, and the second and fourth valves 25 stand at the end of their rocking movement clockwise, Fig. 2.

While the crank-shaft 6 is rotated through

the particular 180 degrees necessary to effect a complete charging or suction stroke of the piston 5 within the cylinder 1, a complete compression stroke of the piston 5 within the cylinder 2, a complete exhausting stroke of the piston 5 within the cylinder 3, and a complete power or firing stroke of the piston 5 within the cylinder 4, the second and fourth valves 25 will have been moved to the limit of its clockwise movement, Fig. 2, and then moved counter-clockwise, whereby the said second and fourth valves will effect the opening and closing of the inlet port 10 of the cylinder 1 and, also, the exhaust port 11 of the cylinder 3 and maintain the exhaust port 11 of the cylinder 2 and the inlet port 10 of the cylinder 4 closed, the exhaust port 11 of the cylinder 1, the inlet ports 10 of the cylinders 2 and 3, and the exhaust port 11 of the cylinder 4 being kept closed by the first, third, and fifth valves 25, which will have been moved counter-clockwise. While the crank-shaft 6 is rotated through the next 180 degrees, the piston 5 within the cylinder 1 makes a complete compression stroke, the piston 5 within the cylinder 2 makes a complete power or firing stroke, the piston 5 within the cylinder 3 makes a complete charging or suction stroke, and the piston 5 within the cylinder 4 makes a complete exhausting stroke, the first, third and fifth valves 25 rocking to the limit of their counter-clockwise movement and then rocking clockwise, thereby effecting the opening and closing of the inlet port 10 of the cylinder 3 and, also, the exhaust port 11 of the cylinder 4 and maintaining the exhaust port 11 of the cylinder 1 and the inlet port 10 of the cylinder 2 closed, and the second and fourth valves 25 continuing to rock counter-clockwise and maintaining the inlet port 10 of the cylinder 1, the exhaust ports 11 of the cylinders 2 and 3, and the inlet port 10 of the cylinder 4 closed. During the next 180 degrees of rotary movement of the crank-shaft 6, the piston 5 within the cylinder 1 makes a complete power or firing stroke, the piston 5 within the cylinder 2 makes a complete exhausting stroke, the piston 5 within the cylinder 3 makes a complete compression stroke, and the piston 5 within the cylinder 4 makes a complete charging or suction stroke, the second and fourth valves 25 rocking to the limit of their counter-clockwise movement and then rocking clockwise, thereby effecting the opening and closing of the exhaust port 11 of the cylinder 2 and, also, the inlet port 10 of the cylinder 4 and maintaining the inlet port 10 of the cylinder 1 and the exhaust port 11 of the cylinder 3 closed, and the first, third, and fifth valves 25 continuing to rock clockwise and maintaining the exhaust port 11 of the cylinder 2, the inlet ports 10 of the cylinders 2 and 3,

and the exhaust port 11 of the cylinder 4 closed. While the crank-shaft 6 is rotated through the next or last 180 degrees necessary to complete a cycle in each cylinder, the 5 piston 5 within the cylinder 1 makes a complete exhausting stroke, the piston 5 within the cylinder 2 makes a complete charging or suction stroke, the piston 5 within the cylinder 3 makes a complete power or firing 10 stroke, and the piston 5 within the cylinder 4 makes a complete compression stroke, the first, third, and fifth valves 25 rocking to the limit of their clockwise movement and then rocking counter-clockwise, with the 15 result of effecting the opening and closing of the exhaust port 11 of the cylinder 1 and, also, the inlet port 10 of the cylinder 2 and maintaining the inlet port 10 of the cylinder 3 and the exhaust port 11 of the cylinder 4 closed, and the second and fourth 20 valves 25 continuing to rock clockwise and maintaining the inlet port 10 of the cylinder 1, the exhaust ports 11 of the cylinders 2 and 3, and the inlet port 10 of the cylinder 25 4 closed.

While it has been hereinabove stated that the cranks of the crank-shaft 6 are so arranged that the power or firing strokes of the pistons 5 occur in the cylinders 1, 2, 3, 30 and 4 in the following order, viz., 1, 3, 4, and 2, yet, it should be understood that the cranks of the crank-shaft may be arranged so that the power or firing strokes of the pistons will follow in any other desired sequence, in which event the valves 25 would be so arranged and their movements so timed as to open and close the inlet ports 10 and the exhaust ports 11 of the cylinders in the proper order. Furthermore, the engine 35 may have a greater or less number of cylinders, in which case a greater or less number of valves 25 would be employed and would be so arranged and their movements so timed as to open and close the inlet 40 ports 10 and the exhaust ports 11 of the cylinders in proper sequence.

While we have herein illustrated and described one form of mechanism that can be employed for actuating the valves, we 50 wish it to be understood that our invention is not limited to such a mechanism, as it is immaterial, so far as our broad idea is concerned, what means is employed for actuating the valves, so long as they are rocked 55 positively in opposite directions to open and close the ports in the cylinders.

An oil-pump 57 and a water-circulating pump 58 may be supported in the housing 46 and have their piston-rods 59 and 60 operatively connected with the blocks 50, respectively, so as to be operated by the latter. The inlet pipe 61 of the oil-pump 57 is connected with an oil-supply receptacle (not shown), and the discharge pipe 62 of 65 the oil-pump leads to an oil-distributing re-

ceptacle 63, from which the oil may be forced through a pipe 64 or a plurality of such pipes to the valve-casings 12 to lubricate the valves 25. In case the engine is used to drive an automobile or the like, several pipes 64 70 may lead from the distributor 63 to any part or parts of the machine requiring lubrication. The inlet pipe 65 of the water-circulating pump 58 is connected with the radiator (not shown) and the discharge pipe 66 75 of the water-circulating pump is connected with the inlet pipe 22 of the water-jacket 20, it being, of course, understood that the outlet pipe 21 of the water-jacket leads to the radiator. By this arrangement, the reciprocating blocks 50 operate the valves 25, the oil-pump 57, and the water-circulating pump 58. The housing 46 may contain a lubricant for blocks 50 and parts associated therewith.

Various changes in the details of construction and arrangement of parts may be made without departing from the nature and spirit of the present invention.

We claim:

1. In an internal combustion engine, the combination of a cylinder having inlet and exhaust ports, and a pair of positively-actuated oscillating valves that act independently of each other, one of said valves controlling one of said ports and the other valve controlling the other port.

2. In an internal combustion engine, the combination of a cylinder having an inlet port and an exhaust port, and two oscillating valves having no direct communication with each other that control said ports independently of each other, both of said valves being moved positively in opposite directions when the engine is in operation.

3. In an internal combustion engine, the combination of a cylinder provided with an inlet port and an exhaust port, two separate and distinct valve casings, one of which communicates with one of said ports and the other with the remaining port, and separate and distinct oscillating valves mounted in said valve casings and operated independently of each other for controlling said ports.

4. In an internal combustion engine, the combination of a cylinder provided with an inlet port and an exhaust port, a hollow rockable exhaust valve that controls said exhaust port, and an independently operated hollow rockable inlet valve that controls said inlet port, said valves having ports that align with the ports in said cylinder so that the exhaust gases can escape through the exhaust valve and the combustible gases can be admitted to the cylinder through 115 said inlet valve.

5. In an internal combustion engine, the combination of a cylinder provided with inlet and exhaust ports in its head, two cylindrical-shaped valve casings extending trans-

- versely across the head of the cylinder, each of which communicates with one of said ports, and positively-actuated rockable valves arranged in said casings for controlling said ports independently of each other. 5
6. In an internal combustion engine, the combination of two adjacent cylinders and a rockable valve that governs the admission of the combustible gases to one cylinder and 10 also governs the exhaust of the burnt gases from the other cylinder.
7. In an internal combustion engine, the combination of two cylinders and a hollow controlling valve provided with a chamber 15 from which the combustible gases are admitted to one cylinder, and a separate and distinct chamber from which the burnt gases are exhausted from the other cylinder.
8. In an internal combustion engine, the combination of two cylinders, a valve casing 20 that communicates with an inlet port in one cylinder and an exhaust port in the other cylinder, an inlet manifold and an exhaust manifold communicating with said 25 valve casing at separated points, and a controlling valve in said casing that governs the admission of the combustible gases to one cylinder and the exhaust of the burnt gases from the other cylinder.
- 30 9. In an internal combustion engine, the combination of two cylinders and an oscillating controlling valve provided with two non-communicating compartments or chambers, one of which is adapted to register 35 with an exhaust port in one cylinder and the other of which is adapted to register with an inlet port in the other cylinder.
10. In an internal combustion engine, the combination of two cylinders and a cylindrical-shaped oscillating valve provided 40 with a longitudinally-disposed partition that divides the interior of same into two compartments, one of which is adapted to register with an inlet port of one cylinder and 45 the other of which is adapted to register with an exhaust port in the other cylinder when the engine is in operation.
11. In an internal combustion engine provided with a cylinder that has an inlet port 50 and an exhaust port formed in its head, two separate and distinct valve chambers extending transversely across the head of the cylinder, and each of which cooperates with one of said ports, an exhaust pipe communicating 55 with one of said valve chambers, an intake manifold communicating with the other valve chamber, said manifolds being located on opposite sides of the engine, and separate and distinct hollow valves oscillating 60 mounted in said valve casings for controlling the inlet and exhaust of the gases to and from said cylinder.
12. A multi-cylinder, four-cycle internal combustion engine provided with oscillating 65 valves arranged in groups, each group comprising a plurality of valves that coöperate with all of the cylinders, and which are so designed and arranged that they will control the inlet and exhaust of the gases to and from the cylinders in proper sequence. 70
13. A multi-cylinder, four-cycle internal combustion engine provided with two groups of oscillating valves that govern the admission and exhaust of the gases to and from the cylinders in proper sequence, each group 75 comprising a plurality of valves, some of which control the inlet of the gases to certain cylinders and the others controlling the exhaust of the gases from the remaining cylinders. 80
14. A multi-cylinder, four-cycle internal combustion engine provided with two groups of oscillating valves, each group comprising a plurality of valves that move in unison and coöperate with all of the cylinders, the 85 valves of one group controlling the inlet ports of certain cylinders and the exhaust ports of the remaining cylinders, and the valves of the other group controlling the ports in the cylinders that are not governed 90 by the first group of valves.
15. A multi-cylinder, four-cycle internal combustion engine provided with groups of positively-actuated valves arranged in such a manner that the valves of one group 95 move in unison in one direction, while the valves of a different group move in unison in the opposite direction, one group controlling the inlet ports of certain cylinders and the exhaust ports of the remaining cylinders and the other group controlling the ports that are not governed by the group of 100 valves first referred to.
16. A multi-cylinder, four-cycle internal combustion engine provided with rockable 105 valves that control the inlet and exhaust of the gases to and from the cylinders in proper sequence, said valves being so designed that the combustible gases do not enter or pass through the spaces in said valves through 110 which the burnt gases escape from the cylinders.
17. A multi-cylinder internal combustion engine, each cylinder of which is provided with an inlet port and an exhaust port, and 115 oscillating valves that govern the ports of said cylinders, certain of said valves controlling two of the ports of adjacent cylinders.
18. A multi-cylinder internal combustion 120 engine, each cylinder of which is provided with an inlet port and an exhaust port, and oscillating valves that govern the ports of said cylinders, certain of said valves controlling the inlet port of one cylinder and 125 the exhaust port of an adjacent cylinder.
19. A multi-cylinder internal combustion engine provided with rockable valves for controlling the inlet and exhaust of the 130 gases to and from all of the cylinders in

- proper sequence, certain of said valves being directly connected together so that they move in unison and arranged so that they control the inlet ports of certain cylinders 5 and the exhaust ports of the remaining cylinders, and the remaining valves being directly connected together and constituting a second group which controls the ports in the cylinders that are not governed by the group 10 of valves first referred to.
20. A multi-cylinder, four-cycle internal combustion engine, each cylinder of which is provided in its head with an inlet port and an exhaust port, a plurality of valve casings, 15 some of which communicate with only one cylinder and the others communicating with a plurality of cylinders, and rockable valves in said casings that are moved positively in opposite directions so as to govern the inlet 20 and exhaust of the gases to and from the cylinders.
21. In an internal combustion engine, the combination of a cylinder having inlet and exhaust ports in its head, rocking valves controlling said ports, rocking members operatively connected with said valves for actuating same, reciprocating members operatively connected with said rocking members for actuating same, a member borne by the 25 crank-shaft having means for actuating said reciprocating members, a housing inclosing said reciprocating members, and the member borne by the crank-shaft, and guiding means for said reciprocating members supported in 30 said housing.
22. In an internal combustion engine, the combination of a cylinder having inlet and exhaust ports in its head, rocking valves controlling said ports, a member having a 35 cam groove in its periphery borne by the crank-shaft, a pair of reciprocating blocks located adjacent to opposite sides of said member, means carried by said blocks adapted to ride in the cam groove in said member, means operative by said 40 blocks for actuating said valves, and guide-rods supporting said blocks.
23. In an internal combustion engine, the combination of a cylinder having inlet and 45 exhaust ports in its head, rocking valves controlling said ports, a member having a cam groove in its periphery borne by the crank-shaft, a pair of reciprocating blocks located adjacent to opposite sides of said member 50 and having complementary grooves in their opposed faces for the reception of said member, guide rods supporting said blocks,
- means carried by said blocks adapted to ride in the cam groove in said member, and means operative by said blocks for actuating 60 said valves.
24. In an internal combustion engine, the combination of a cylinder having inlet and exhaust ports in its head, valves controlling said ports, a member having a cam groove in its periphery borne by the crank-shaft, a pair of reciprocating blocks located adjacent to opposite sides of said member, means carried by said blocks adapted to ride in the cam groove in said member, means operative by 65 said blocks for actuating said valves, and means for lubricating said valves including a pump operative by one of said blocks adapted to force a lubricant to said valves. 75
25. In an internal combustion engine, the combination of a cylinder having inlet and exhaust ports in its head and provided with a water-jacket, valves controlling said ports, a member having a cam groove in its periphery borne by the crank-shaft, a pair of reciprocating blocks located adjacent to opposite sides of said member, means carried by said blocks adapted to ride in the cam groove in said member, means operative by 80 said blocks for actuating said valves, and a water-circulating pump operative by one of said blocks and having a connection with the water-jacket. 85
26. In an internal combustion engine, the combination of a cylinder having inlet and exhaust ports in its head and provided with a water-jacket, valves controlling said ports, a member having a cam groove in its periphery borne by the crank-shaft, a pair of reciprocating blocks located adjacent to opposite sides of said member, means carried by 90 said blocks adapted to ride in the cam groove in said member, means operative by said blocks for actuating said valves, a water-circulating pump operative by one of said blocks and having a connection with the water-jacket, and means for lubricating said valves including a pump operative by the other of said blocks adapted to force a lubricant to said valves. 100

In testimony whereof we hereunto affix our signatures in the presence of two witnesses.

WALTER F. KOKEN.

H. D. PARRY,
A. JOHNSON.

It is hereby certified that in Letters Patent No. 1,161,221, granted November 23, 1915, upon the application of Walter F. Koken and Anton J. Pichl, of St. Louis, Missouri, for an improvement in "Valve Mechanisms for Internal-Combustion Engines," an error appears in the printed specification requiring correction as follows: Page 2, line 116, strike out the word "by"; and that the said Letters Patent should be read with this correction therein that the same may conform to the record of the case in the Patent Office.

Signed and sealed this 14th day of December, A. D., 1915.

R. F. WHITEHEAD,

Acting Commissioner of Patents.

[SEAL.]

Cl. 123—81.
